UNITED STATES PATENT OFFICE.

BENJAMIN F. MAYO, OF SALEM, MASSACHUSETTS, ASSIGNOR, BY MESNE ASSIGNMENTS, TO THE UNITED SHOE MACHINERY COMPANY, A CORPORATION OF NEW JERSEY.

RACEWAY FOR NAIL-ASSORTING MACHINES.

SPECIFICATION forming part of Letters Patent No. 707,142, dated August 19, 1902.

Application filed May 24, 1898. Serial No. 681,612. (No model.)

To all whom it may concern:

Be it known that I, BENJAMIN F. MAYO, of Salem, county of Essex, State of Massachusetts, have invented an Improvement in Raceways for Nail-Assorting Machines, of which the following description, in connection with the accompanying drawings, is a specification, like letters on the drawings representing like parts.

- 10 In machines for assorting nails the nails laid in grooves of the raceway heads and points indiscriminately are led to apparatus for insuring the delivery of said nails with their heads or points all in one direction.
15 The nails used are headless, and there is no way of discharging from the raceway-grooves imperfect nails or slivers of metal.

This invention has for its object an improved construction of the raceway and grooves, whereby any small nails or slivers may be discharged before arriving at the end of the raceway.

In accordance with my invention I provide each raceway-groove with a tapered slot arranged in the general direction of the length of and preferably substantially coinciding for a part or the whole of its length with said groove, said slot being of a length preferably a little greater than the length of the nails to 25 be assorted, the narrowest part of each of said slots being represented as extended upwardly in the direction of the length of the groove, one end (herein represented as the lower end) of each of said slots being provided, preferably, with an enlarged opening.
30

Figure 1, in plan view, shows part of a raceway provided with my improvements; Fig. 2, a section thereof in the dotted line x , and Fig. 3 a partial cross-section in the line x' .

40 The metallic bed or plate A, as herein shown, has a series of grooves a made in rising portions of the plate, and the face of the bed between the said grooves is concaved, as at b , the lower ends of the concaved spaces being provided with open spaces b' , through 45 which may drop any nails thrown on the raceway-plate which do not enter the raceway-grooves a . Each groove a is provided with a tapered slot a' and, as shown, with a hole

a^2 . The wider part of the slot starts at the 50 hole a^2 and, as herein represented, is carried toward the upper end of the plate, and the slot is preferably longer than the length of the nails to be assorted, said slot being cut through the groove in the general direction 55 of its length and preferably so as to substantially coincide for a part of its length with said groove, the slot shown being represented as removing more stock from one than from the other side wall of the groove. With this 60 slot in the groove any perfect nails of a diameter greater than the width of the slot, whether head or point first, will readily pass the hole a^2 , but if a nail smaller or shorter than the regular nails being assorted comes in position 65 above said slot said sliver immediately drops into and through said slot into a suitable receptacle c , located below the plate A. When the smaller end of the sliver leads, it will drop through the slot immediately, as shown by 70 dotted lines, Fig. 2, while if the larger end of the sliver leads it will not drop until the said larger end arrives above the hole a^2 . The hole a^2 is of a diameter greater than the width of the groove.
75

At the left in Fig. 1 I have shown a series of nails of proper size running down the raceway-groove.

Having described my invention, what I claim as new, and desire to secure by Letters 80 Patent, is—

1. A raceway presenting a groove provided in its bottom with an uncovered slot arranged in the general direction of said groove, said slot being longer than the nail being handled. 85

2. A raceway having a groove provided with a slot arranged in the general direction of said groove, with an enlargement at the end of said slot, said slot being longer than the nail being handled.
90

3. A raceway having a groove provided with a slot arranged in the general direction of said groove, and with an enlargement at the end of said slot.

4. A raceway having a groove provided with a tapered slot arranged in the general direction of said groove.
95

5. A raceway having a groove provided with

a tapering slot located in the general direction of said groove, and a hole intersecting said slot, to operate substantially as described.

6. A raceway having a groove, and a tapering slot made therein in the general direction of the length of said groove, said slot removing more stock from one than from the other side of said groove.

7. A raceway having a groove provided with a slot arranged in the general direction of the groove, and a hole intersecting said slot, said hole being of greater diameter than the width of the groove and located in the bottom of said groove.

8. A raceway having a groove provided with a tapered slot formed therein in the general

direction of the length of said groove, the wider end of said slot being located nearest the lower end of the raceway-groove.

9. A raceway having a groove provided with a tapered slot formed therein in the general direction of the length of said groove, said slot being of greater length than the nail being handled.

In testimony whereof I have signed my name to this specification in the presence of two subscribing witnesses.

BENJAMIN F. MAYO.
